UNITED STATES PATENT OFFICE.

MICHEL SANTOIANNI, OF CHICAGO, ILLINOIS.

DESIGN FOR A TOY BABY CAB.

Application filed December 24, 1921. Serial No. 524,779. Term of patent 7 years.

To all whom it may concern:

Be it known that I, MICHEL SANTOIANNI, subject of the King of Italy (having heretofore declared his intention of becoming a citizen of the United States), having residence in the city of Chicago, county of Cook, and State of Illinois, have invented a new, original, and ornamental Design for Toy Baby Cab, of which the following is a specification, reference being had to the accompanying drawings, forming a part thereof.

The drawing is a perspective view of a toy baby cab embodying this design.

I claim:

The ornamental design for a toy baby cab as herein shown and described.

In testimony whereof, I have hereunto set my hand this 22nd day of December, 1921.

MICHEL SANTOIANNI.
